UNITED STATES PATENT OFFICE.

EUGENE S. BIDDLE, OF MUNCY, PENNSYLVANIA.

AUTOMATIC CONTROLLING APPLIANCE FOR RAILWAY-TRAINS.

1,297,783.

Specification of Letters Patent. Patented Mar. 18, 1919.

Application filed April 20, 1918. Serial No. 229,721.

To all whom it may concern:

Be it known that I, EUGENE S. BIDDLE, a citizen of the United States of America, residing at Muncy, in the county of Lycoming and State of Pennsylvania, have invented 5 certain new and useful Improvements in Automatic Controlling Appliances for Railway-Trains, of which the following is a specification.

10 This invention relates to improvements in what may be termed automatic controlling appliances for railway trains.

The invention has primarily for its object to automatically effect the application 15 of the air-brakes of a railway train for retarding the movement thereof at required points or stations and to carry out that end in a simple, ready and effective manner.

20 Further objects of the invention will suggest themselves as the nature of the invention is more fully made known and its characteristics are later pointed out and the invention therefore consists of certain instrumentalities and features of construction substantially as hereinafter fully described and 25 defined by the claims.

In the accompanying drawing is illustrated the preferred embodiment of my invention wherein it will be understood that 30 various changes and modifications as to the detailed construction and arrangement of parts may be made without departing from the spirit or scope of the appended claims, and in which drawings:

35 Figure 1 is a view in side elevation showing my invention as applied for use in connection with an engine of the locomotive type and its trackage;

40 Fig. 2 is a similar view of the same, with the engine cab shown skeletonized or diagrammatically;

45 Fig. 3 is an enlarged detailed view of the star-wheel trip-rod and the automatic air-brake valve connection;

50 Fig. 4 is a fragmental sectional view, showing my invention, in part, applied to the engineer's lever, for controlling the air-brakes.

55 Fig. 5 is a plan view of the parts shown in Fig. 4;

Fig. 6 is a fragmental detailed view showing the guide and vertically retaining means for the train stop rod-member.

Fig. 7 is a side view of the lever 20.

Fig. 8 is a plan view of pawl and ratchet 55 mechanism.

Fig. 9 is a detail view partly in section of the pinion 17 and associated parts.

Fig. 10 is a bottom plan view of the disk 6.

Fig. 11 is a plan view of the star wheel, 60 and

Fig. 12 is a detail view of the lever mechanism for oscillating the rod 1.

In carrying out my invention I suitably position along the trackage or railway A, 65 upon the outside of the right-hand rail, preferably a tubular rod-like or pipe member 1, the same being suitably and fixedly supported in any suitable way, upon the rail-ties as shown, said rod or pipe member 70 being equipped with a plurality of tiltable projections 2 intervalled apart say twenty-five feet, there being preferably eight of these projections or "stops," and projecting about five or six inches from said rod; the 75 length of said projections, however, may be varied as desired. The rod or pipe 1 is adapted to be operated, together with the signal or semaphore (not shown) by means of a manually actuated lever 3, positioned 80 within a station or signaling tower (not shown).

A preferably star-like-spoked rotary member or wheel 4 adapted to engage the projections 2 of the reciprocal rod 1, is fixed, 85 to occupy a horizontal position, to the lower end of a rod 5 rotatably depending from, and through the floor of the engine-cabin B, and suitably connected to the engineer's lever for controlling the air-brakes (not 90 shown) and whereby, as engagement is effected by the spokes of the wheel or member 4 with the projections 2, during the travel of the engine or train, the air-brakes are gradually applied and the train slowed 95 down.

An undulatory-faced member or disk 6 is adapted to serve as a safety device to prevent the rod 5 and star wheel or member 4 turning any more than one eighth of the 100 distance traveled at one time, said disk being secured to the underside of the engine cab-floor, and the face of this member or disk 6 forcibly engages a resilient detent or dog 7 carried by the rod 5 whereby the rotation of the rod 5 and star-wheel 4 is retarded.

The rod 5 has applied thereto within the

engine-cab B, means for its retention, as against vertical or lateral displacement, comprising what may be termed a base-plate 8 suitably bolted as at 8^a to the cab-floor and through which and the cab-floor said rod passes, said base-plate having an upraised groove or race 9 containing a plurality of anti-frictional balls or bearings 10, providing for reducing friction and the free turning movement of the rod. Overlying and resting upon the base plate 8 is a keeper 11 housing the antifrictional preferably steel balls 10 within the groove or race 9 but not interfering with the mobility thereof, the fastening bolts 8^a for securing the base plate or disk to the cab-floor serving to secure said keeper in its place. Resting upon and preventing the upward displacement of the bearings or balls 10, and positioned intermediate thereof and the keeper 11 is a cap 12 having a tubular neck-portion 13 extending upwardly through an opening in the keeper 11, and a short distance around and receiving the rod 5, said neck having a headed and nut-equipped bolt 14 passing therethrough and through said rod for the retention of said cap in place upon the latter.

A ratchet 15 is suitably applied to the rod or shaft 5, within the engine-cab B and has engaged therewith a resiliently controlled pawl 16 for returning the handle of the engineer's lever to off position.

Applied or fixed to the upper end of the rod or shaft 5 is a cog wheel or pinion 17 supported in a bracket 18, secured to the engine boiler, said pinion or cog being intergeared with a link or rack-bar 19 connected to a lever 20 of the air-brake-valve 40. As shown in Fig. 4, the stem 21 extends up through the automatic brake-valve and receives thereon the engineer's lever 3'. The lever 20 is adapted to fit upon an upward extension 23 on the engineer's lever 3' and is formed with a lug or extension 22 which engages or contact with said engineer's lever 3', whereby movement of the lever 20 is communicated to the engineer's lever. It will thus be seen that the air-brake valve will be actuated through this arrangement during the movement of the engine or train and the engineer's lever be accordingly operated or thrown by the lug 22 and the air-brakes be simultaneously applied, bringing the engine or train to a stop.

As previously stated, it will be appreciated that numerous changes may be resorted to in the various details as relates to improving and substituting parts so long as these fall within the breadth of my invention as covered by the claims appended hereto.

I claim:

1. A device of the type described including means positioned alongside a track-rail, means carried by a moving body adapted to cooperate with the aforesaid means, an en-

gineer's lever having a tubular extension, and air-brake controlling means comprising a valve, the stem of which is adapted for the application thereto of said tubular extension of the engineer's lever, said air-brake valve having connected thereto a rack, intergeared with the means cooperating with the means positioned along the track-rail, said air-brake lever having a pendent stud laterally engaging said engineer's lever. 75

2. A device of the type described, including means embracing a shaft paralleling the railway track and carrying tiltable projections disposed along the rail of the track, a rotary spoked actuating means for engaging said tiltable projections, air-brake controlling means, an engineer's lever, and intermediary means for effecting engagement with said tiltable projections and means causing said brake controlling means to throw said engineer's lever. 80

3. The combination with a moving body along the rails of a railway, depressible projections positioned upon a member paralleling said rails, a member carried by said moving body and adapted to engage said depressible projections, means for imparting an intermittently rotary movement to the intermittently rotary member, air-brake-actuating means, an engineer's lever arranged to be automatically actuated by said air-brake actuating means, means intermediary of said depressible projection engaging means and said air-brake actuating means, for causing said air-brake actuating means to throw said engineer's lever, and means to effect the intermittent rotary movement of said projection engaging means. 90

4. The combination of means having depressible projections arranged along a railway rail, a means having an intermittent rotary motion and adapted to engage said depressible projections, an air-brake valve actuating means, an engineer's lever, means intermediary said means, and said air-valve actuating means for actuating said rotary means, and causing said air-brake actuating means to throw said engineer's lever. 105

5. The combination of means having depressible projections and positioned for actuation along a railway rail, a rotary means for engaging said projections, an air-brake actuating means, a member carrying said rotary means, an intergeared rack-bar and pinion between said rotary carrying member and said air-brake actuating means, said air-brake actuating means and said engineer's lever being adapted for co-operation and including a lever intermediary of said engineer's lever and said intergeared rack-bar whereby said air-brake means if adapted to throw said engineer's lever. 115

6. In a device of the type described, the combination with means having depressible projections positioned along a railway rail, 130

means adapted to engage said depressible projections, means carrying said depressible projection engaging means, means for actuating said carrying means, and an undulatory faced member positioned upon said carrying means, said carrying means being provided with a resiliently controlled means for engagement with said undulatory faced member, said undulatory faced member to

predetermine the intermittent movement of 10 said carrying means and the means for engaging said depressible projections.

In testimony whereof I affix my signature in presence of two witnesses.

EUGENE S. BIDDLE.
